(57) **CLAIM**

The ornamental design for a retrofit assembly platform for modular refrigeration system, as shown and described.

DESCRIPTION

FIG. 1 is a front perspective view of a retrofit assembly platform for modular refrigeration system, showing the first embodiment of my new design;

FIG. 2 is a front view of FIG. 1;

FIG. 3 is a rear view FIG. 1;

FIG. 4 is a right side view of FIG. 1;

FIG. 5 is a left side view of FIG. 1;

FIG. 6 is top view of FIG. 1; and,

FIG. 7 is a front perspective view of a retrofit assembly platform for modular refrigeration system, showing the second embodiment of my new design.

The broken lines shown in the drawings represent unclaimed subject matter and form no part of the claimed design.
